UNITED STATES PATENT OFFICE.

DANIEL BROWN, OF NEW YORK, N. Y.

DESIGN FOR A CANE.

No. 37,517.

Specification for Design.

Patented Aug. 29, 1905.

Application filed February 23, 1905. Serial No. 247,054. Term of patent 3½ years.

To all whom it may concern:

Be it known that I, DANIEL BROWN, a citizen of the United States, residing at New York, in the county of New York and State of New York, have invented a new, original, and ornamental Design for Canes.

The figure of the drawing is an elevation of a cane, showing my design.

I claim—

The ornamental design for a cane, as shown.

DANIEL BROWN.
